UNITED STATES PATENT OFFICE

LEE BARTON WILLIAMS, OF PITTSBURGH, PENNSYLVANIA

TOY PROJECTILE

Application filed September 29, 1931. Serial No. 565,857.

This invention relates to toys of the projectile type, the primary object of the invention being to provide a device which may be projected into the air by any suitable means, 5 the device being so constructed that a parachute carried thereby, will be released as the device starts to descend, to the end that the projectile will float gracefully to the earth, affording amusement for the spectators.

10 An important object of the invention is the provision of a device of this character comprising a body portion formed of hingedly connected sections, within which a parachute is folded, novel means being provided to automatically open the body portion, releasing the parachute to support the body portion in its downward flight.

15 A further object of the invention is to provide means for normally holding the sections of the body portion in their closed positions, means being provided and operated by the turning of the body portion in the air for opening the sections of the body portion.

20 With the foregoing and other objects in view, which will appear as the description proceeds, the invention resides in the combination and arrangement of parts and in the details of construction hereinafter described and claimed, it being understood that changes 25 in the precise embodiment of the invention herein disclosed, may be made within the scope of what is claimed, without departing from the spirit of the invention.

30 Referring to the drawing:

35 Figure 1 is an elevational view of the projectile in its open condition and supported by the parachute.

Figure 2 is an elevational view of the body portion or projectile in its closed position.

40 Figure 3 is a fragmental sectional view of the body portion illustrating the latch and actuating means in detail.

Figure 4 is a sectional view taken approximately on line 4-4 of Figure 2.

45 Referring to the drawing in detail, the projectile which is indicated generally by the reference character 5 is hollow in construction, the same being constructed of light material to offer little resistance as it is being projected into the air.

As shown, the body portion comprises sections 6 and 7 connected by means of the spring hinges 8 which normally act to urge the sections to their open positions.

55 The body portion is constructed to simulate the human body, the foot and leg portions of the body being weighted so that when the device is shot into the air feet first, the body portion will turn causing the body portion to descend feet first.

60 Supported within one of the sections of the body portion, is a tube indicated by the reference character 9, which tube is closed at the end nearest the head of the body portion, while the opposite end of the tube is 65 open to accommodate the free end of the pivoted latch 10, which is carried by the opposite section of the body portion.

66 Due to the construction of the body portion, the pivoted latch is held in its latching position, by the frictional contact between the latch and body portion, caused by the action of the spring hinges 8.

70 The reference character 11 designates a ball which is supported within the tube 9, the ball being free to move longitudinally of the tube, when the body portion is turned end for end.

75 Thus it will be seen that when the projectile is shot into the air feet first, the ball will lie at the lower end of the tube, or near the head of the body portion, but when the body portion loses its momentum and is inverted, the ball will fall to the opposite end 80 of the tube, striking the free end of the pivoted latch to cause the latch to move to release the sections of the body portion.

85 The sections of the body portion will now swing open to positions as shown by Figure 90 1 of the drawing.

95 The reference character 12 designates a parachute which is connected to the head 13, by means of the cord 14.

100 The parachute is of a construction to be folded within the body portion between the sections thereof, so that when the body portion is opened, the parachute will unfold and assume a position as shown by Figure 1 thereby offering resistance and causing the

body portion to float gradually to earth, affording amusement to the spectators.

The reference character 15 designates a whistle of the type operated by the air rushing through the whistle. Thus it will be seen that as the device is shot into the air, a whistling sound will be produced to attract the attention of people standing near the operator of the device.

10 Although the body portion has been shown and described as in a form to simulate the human body, it is to be understood that the design of the body portion may be changed to meet various requirements, without departing from the spirit of the invention.

15 While I have not illustrated the means for projecting the body portion into the air, it is to be understood that any suitable means such as a sling shot or similar mechanism may be employed for this purpose.

I claim:

20 1. A projectile toy comprising a hollow body portion including hingedly connected sections, means for urging the sections to their open positions, a latch at one end of the body portion for normally holding the sections of the body portion closed, a tube within the body portion and extending to one end of the body portion, said latch member extending into the tube, a weight within the tube and adapted to gravitate to one end of the tube releasing the latch, and a 25 parachute held within the body portion, and adapted to unfold to support the body portion when the body portion opens and floats to the earth.

30 2. A projectile toy comprising a hollow body portion including hingedly connected sections, means for normally urging the sections to their open position, a latch member for normally holding the sections of the body portion closed, a weight within the body portion, means for guiding the weight into engagement with the latch releasing the latch to open the body portion, and a 35 parachute held within the body portion and adapted to unfold when the body portion opens.

40 50 In testimony that I claim the foregoing as my own, I have hereto affixed my signature.

LEE BARTON WILLIAMS.
